CURTAIN AND DRAPE BRACKET

Immacolata Pisciotta, New York, N. Y.

Application July 6, 1937, Serial No. 152,179

1 Claim. (Cl. 248—254)

This invention relates to improvements in curtain supporting means and more particularly to an improved type of bracket arm which is adapted to hold a plurality of curtains positioned before a window.

Notable among the advantages of the present invention is the feature that it provides means for attaching a plurality of drapes and curtains by one support without necessitating individual supports for each set as has heretofore been the case.

Another feature of the present invention is that it provides means for supporting both curtains and drapes upon one mounting means and in addition thereto permits the drapes to be moved outwardly away from the window when it is desired to free same from obstruction.

Another notable feature of the present invention is that it provides a structure of the type before indicated which is simple, not readily broken or put in disrepair, and which can be easily and economically manufactured.

The invention will be fully and comprehensively understood from a consideration of the following detailed description when read in connection with the accompanying drawing which forms part of the application.

In the drawing:

Fig. 1 is a perspective view of one embodiment of the matter of the present invention with a portion of a curtain support shown in position.

Fig. 2 is a perspective view of the bracket prepared in accordance with the present invention; and

Fig. 3 is a top plan view of the formed bracket, and

Fig. 4 is a top plan view of the blank from which the bracket is formed.

Referring to the drawing, the bracket illustrated in Fig. 2 is formed by shaping a piece of material, preferably metal or the like, into substantially the outline indicated in Fig. 4. This can be effected by stamping, cutting or other means as desired, the thickness of stock to be used being largely determined by the strength of the material and the weight of the objects to be supported.

Referring to Fig. 4, the portion of the cut-out member generally designated at 5 is bent along the dotted line indicated at 6 so that it is disposed substantially at right angles to the remainder of the object. This portion 5 serves as a mounting or base of the bracket and is pierced by the openings 7 and 8 which are adapted to receive screws for mounting the bracket upon the

wall or window frame. The lugs generally designated at 8 are bent along the dotted lines indicated at 9 and turned back against the body of the bracket 10 with the portions 11 bent upright and disposed substantially at right angles to said body 10 substantially as shown in Figs. 2 and 3. The other end of the major portion of the bracket generally designated as 10 is rolled back upon itself to form a substantially cylindrical member generally designated as 12.

In use, the portion of the bracket generally designated at 5 is attached to the window frame or wall structure by screws or like fastening means, and a curtain supporting means generally designated as 30 is positioned over the extended lugs, generally designated as 11, of the bracket member. A plurality of these members being used in conjunction, it will be apparent that the curtain supporting means 30 will relatively fixedly position the curtains attached thereto. The bracket arm 31 which is bent to resemble an L-shape is rotatably positioned within the cylindrical end portion of the bracket generally designated at 12 so that it is free to rotate about this pivotal axis, accordingly, the drapes supported thereon can be moved, if desired, from their position adjacent to the curtains as shown in Fig. 1 to other positions as the user may desire from time to time.

It will be apparent to those skilled in the art that variations can be made in the design of the bracket arm prepared in accordance with the present invention to adapt it to use with other types of curtain supporting means than the flat hollow extensible members described herein in connection with the preferred embodiment of said invention. For example, the lugs 11 can be replaced by members such as pins, hooks and the like, adapted to engage with other types of curtain supporting means. It is also evident that without departing from the spirit of the present invention other means can be provided for mounting the bracket arm generally designated as 31 in a rotatable manner upon the bracket proper. For example, a pin could be fixedly positioned in the bracket proper and the bracket then could comprise a bossed substantially lever-like arm engageable with said pin and rotatable thereon.

It is to be understood that this improvement is capable of extended application and is not confined to the exact showing of the drawings nor to the precise construction described and, therefore, such changes and modifications may be made therein as do not affect the spirit of

the invention nor exceed the scope thereof as expressed in the appended claim.

What is claimed as new is:

A combination bracket for supporting a set of window curtains and drapes disposed adjacent thereto, said bracket comprising a plate-like member having lugs formed from the substance of said member and integral therewith and located at an intermediate point on said member, said 10 lugs being bent back against the side of said

member and having portions thereof cut and bent whereby the bent portions are disposed in a common plane, said cut and bent portions presenting projecting elements disposed in a plane substantially perpendicular to the plane of said member and adapted to engagement with curtain supporting means, and means at one end of the bracket adapted to receive a support for drapes. 5

IMMACOLATA PISCOTTA. 10
